Des. 203,107
Patented Dec. 7, 1965

203,107

BASEBALL EQUIPMENT CARRY-ALL

Frank V. Hardy, 6502 Brittain St., Long Beach, Calif., and Jim R. Galceran, 3171 Yellowtail Drive, Los Alamitos, Calif.

Filed Feb. 16, 1965, Ser. No. 83,835

Term of patent 14 years

(Cl. D14—3)

The side not shown has substantially the same appearance as the side shown in the figures.

We claim:

The ornamental design for a baseball equipment carry-all, substantially as shown and described.
